UNITED STATES PATENT OFFICE.

CHARLES A. BEYERS, OF KANE, PENNSYLVANIA.

SHOE-POLISHING STAND.

1,226,053.

Specification of Letters Patent. Patented May 15, 1917.

Application filed September 2, 1915. Serial No. 48,671.

To all whom it may concern:

Be it known that I, CHARLES A. BEYERS, a citizen of the United States, residing at Kane, in the county of McKean and State 5 of Pennsylvania, have invented certain new and useful Improvements in Shoe-Polishing Stands, of which the following is a specification.

This invention relates to the class of shoe 10 polishing apparatuses and is more particularly concerned with the provision of a stand so constructed as to conveniently contain all of the articles employed in the polishing of shoes, as well as being equipped 15 with means enabling the user to polish his own shoes without stooping.

A further object is the provision of a stand of the character described which may be almost entirely constructed from a single 20 length of heavy bent wire in order to secure not only the tray containing the articles when not in use but also conveniently supporting the polish can and the foot of the user, while in addition so directing the 25 course of a polishing rag as to render the operation far less laborious and much more satisfactory as to the polish secured.

The above and additional objects which 30 will become apparent as this explanatory description proceeds, are accomplished by such means as are illustrated in the accompanying drawings, described in the following specification and then more particularly pointed out in the claims which are 35 appended hereto and form a part of this application.

With reference to the drawings, wherein 40 there is illustrated the preferred embodiment of this invention as it is reduced to practice, and throughout the several views 45 of which like characters of reference designate similar parts:

Figure 1 is a front elevation of the shoe 45 shining stand comprehended by this invention,

Fig. 2 is a plan view of the matter disclosed in Fig. 1,

Fig. 3 is a central longitudinal sectional view through the stand, and

Fig. 4 is a perspective illustration of the 50 manner of employing the stand to advantage.

In the embodiment illustrated, the bottom tray which also serves as a supporting 55 base for the entire stand is designated 5 and is provided with perimetral walls 6 in which

the articles such as polishing rags, daubing rags, cans and bottles of polish, etc., employed with the stand may be readily contained. As shown this tray is oblong, and 60 although no limitation as to such shape is intended, the description of the device is facilitated thereby. The wire forming what may be termed the shoe supporting structure is intermediately secured along 65 the bottom edge of each of the tray ends as denoted at 7 and is then bent upwardly to form the upright portions 8 which are placed in the respective planes of the tray sides. Both pairs of these uprights 8 are 70 integrally connected by a horizontal portion 9, one of which portions is prolonged and then successively bent upon itself to form the square inclosure 10. Transverse supports 11 extend from one bent portion of the 75 inclosure 10 to an opposite bent portion in order to support a suitable box or can of polish. Braces 12 extend transversely above the tray 5 in securing opposite pairs of the members 8. Fastening devices 13 of any 80 desired description are employed at the several corners of the tray 5 in order to maintain the shoe supporting structure in its proper position.

The integral portions 9 each support a 85 plate 14 which is rolled thereover, one of the dependent portions of the plate being formed with the horizontal flange 15 while through both of the sides of each plate there projects the screw or similar pivoting member 16 whereby a foot plate 17, preferably constructed from wood or a material similarly desirable is supported in spaced relation to the flanges 15 as is clearly apparent from an inspection of Fig. 3. Wear plates 95 18 may be provided for the extremities of this foot rest at the point where the latter contacts with the rolled plate 14.

In use the operator assumes his position by the side of the stand and places his foot 100 upon the rest 17. The tray 5 gives easy access to the materials employed in the preliminary process of polishing shoes, while the inclosure 10 supports the can of polish. When the final operation of placing the high 105 polish upon the surface of the shoe is reached, the operator threads a cloth or strip of felt over the foot rest 17 and beneath each of the braces 12 in the manner clearly illustrated, placing the shoe to be 110 polished between the bight portion of the cloth and the rest 17. By then successively

pulling upon each extremity of the strip in the obvious manner, the user of the present device will be able to procure a high polish upon his shoes without the backbreaking labor hitherto necessitated. It should also be noted that the braces 12 serve as points of leverage whereby any desired degree of frictional contact between the bight portion of the polishing cloth and the top of the shoe may be gained by exerting a strain upon the ends of the polishing strip.

While in the foregoing, however, there has thus been illustrated in the drawings and described in the specification such combination and arrangement of elements as constitute the preferred embodiment of this invention, it is desired to emphasize the fact that such minor changes in the matters of proportion and degree may be made in later adaptations of this device as shall not alter the spirit of the invention as defined in the appended claims.

What is claimed is:—

1. A polishing stand for shoes including a base tray, upright supports on two opposite sides of said tray extending in parallel planes, each support comprising a wire bent

into substantially U-shape with horizontal top and outwardly inclined legs fastened at their lower ends to the corners of said tray on one side, a horizontal inclosure formed integrally of the wire of one of said supports projecting outwardly from the top of the same, braces joining the horizontal top portions of said supports and forming guides for a polishing cloth, and a foot rest pivoted in parallelism between said braces to rock laterally.

2. A polishing stand including a base tray, uprights secured to said tray at each side thereof, transverse braces joining the uprights of opposite sides, plates carried by said uprights between said braces and formed with abutment flanges, and a foot rest pivotally supported by said plates in parallelism to said braces and adapted to have its movement limited by contact with said flanges.

In testimony whereof I affix my signature in presence of two witnesses.

CHARLES A. BEYERS.
